REMOTE CONTROL UNIT

Wallace A. Monson, Golden Valley, Minn., assignor to Minneapolis-Honeywell Regulator Company, Minneapolis, Minn., a corporation of Delaware

Filed June 22, 1961, Ser. No. 65,684

Term of patent 3½ years

(Cl. D26—13)

FIGURE 2 is a front view of the unit of FIGURE 1,

FIGURE 7 is a bottom view of my remote control unit.

I claim:

The ornamental design for a remote control unit, substantially as shown.
